UNITED STATES PATENT OFFICE.

ALDEI LANDRY, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

KNITTED HOSIERY.

1,413,337.

Specification of Letters Patent. Patented Apr. 18, 1922.

Application filed March 12, 1919. Serial No. 282,077.

To all whom it may concern:

Be it known that I, ALDEI LANDRY, a citizen of the United States, and a resident of Central Falls, in the county of Providence and State of Rhode Island, have invented an Improvement in Knitted Hosiery, of which the following description, in connection with the accompanying drawings, is a specification, like characters on the drawings representing like parts.

This invention relates to improvements in knitted hosiery and to the method of forming the same.

The invention contemplates the production of an economical, sanitary stocking of neat appearance and in which substantially all points or areas that are subjected to excessive or more than ordinary wear are formed from special yarns of heavier or more durable character than those comprising the less important parts thereof.

The invention consists in the combination and arrangement of the various sections or areas of the stocking and in a mode of forming the same, whereby the above objects and other objects hereinafter appearing may be attained as set forth in the following specification and particularly pointed out in the claims.

Referring to the drawings—

Fig. 1 is a side elevation of a stocking embodying the preferred characteristics of my invention including a high splice so-called.

Fig. 2 is a detail side elevation of the heel portion of a stocking in which the high splice has been omitted.

The invention has to do more particularly with the formation of the heel and adjacent portions of the stocking and, although in the accompanying drawings I show what I believe to be the most approved construction, it is, however, to be distinctly understood that the invention is not limited to the forms shown.

In the ordinary type of stocking wherein a high splice is employed in connection with what may be termed a sanitary foot, i. e., a foot formed partially or entirely of undyed or light colored yarn, the high splice is sometimes extended to the point in the heel below the ankle (and by the term ankle, in the present case, I mean the beginning of the narrowing courses which form the heel pocket) at which point juncture is made with the yarn from which the foot is formed.

By this method the light colored yarn of the foot will never be exposed above the top of even the lowest cut shoe.

In high grade hosiery and especially in hosiery constructed of silk the area above the heel is reinforced or provided with a high splice, so-called, that is, it is constructed of a plurality of yarns or of a much heavier yarn than that from which the other portions of the leg of the stocking are formed and, as the greater portion of this area is often exposed to view, it must be made of yarn similar in nature to that forming the leg of the stocking so that the cost of producing the stocking must be materially increased.

It is the purpose of this invention to reduce the cost of producing stockings of the nature set forth by effecting a material saving in the yarn constituting said high splice. This saving I preferably effect by constructing the high splice of a heavier grade of silk from the top thereof to the ankle of the stocking at which point the heavy silk is withdrawn and a heavy mercerized yarn of substantially the same weight as that constituting said high splice, is substituted and from this yarn that portion of the heel is formed which extends from the ankle of the stocking to a point far enough below said ankle to cover all areas of the heel likely to show above the top of the shoe. The section formed of said mercerized yarn is essentially of the same color as the high splice area and the high splice area is of the same color as the leg of the stocking. For instance, assuming that the stocking is made of black yarn with white foot, the black yarn will be employed from the top 1 of said stocking throughout the tubular leg portion 2 thereof to the point in the heel below the ankle heretofore referred to and from said point white or undyed yarn will be employed either throughout the entire area of the foot of said stocking or in certain sections thereof, such as at the heel and toe portions of said stocking.

It is, however, to be distinctly understood that the yarns employed in the construction of the formation of the stocking may be of any suitable character even to the extent of being in so far as color is concerned all alike throughout the entire area of the stocking. Preferably they contrast in one or more ways, such as in color, material, etc. My

invention, however, is in no wise limited in this respect.

In the production of the stocking embodying my invention, I preferably though not necessarily, begin the knitting at 1 and for the purpose of contrast will assume that the yarn to be used in this operation is black. We will further assume that the stocking is to be knitted upon a knitting machine of the 10 type known as a circular knitting machine and in which type the needle cylinder is both rotary and rotary-reciprocal, as is customary in stocking knitting machines in general use at the present time.

15 Beginning at the top 1 of the stocking the needle cylinder is rotated to produce the tubular leg 2 in the usual manner and from black or dark colored yarn to the top line 3 of the high splice.

20 As one of the essential advantages of the invention is to effect economy in construction, the formation of the stocking from the top of the high splice to the toe thereof is effected through the rotary reciprocal 25 movements of the needle cylinder to produce a split fabric, that is, a fabric in which the front and rear sections are composed of different yarns thereby eliminating the floating yarns, so-called, requiring an extra amount 30 of very careful work in removing same, to say nothing of the large amount of yarn wasted in such operation.

To accomplish the desired results the yarn from which the tubular leg 2 is constructed 35 will be withdrawn at 3 and the motion of the needle cylinder will be changed from rotary to rotary reciprocal.

The knitting cams which act upon the needles to knit the tubular portion 2 will 40 now be used to act only upon approximately one half of the circular series of needles to effect the knitting of the high splice 4 preferably with heavy silk yarn substituted for the yarn previously employed down to the 45 line 3; said heavy yarn being preferably of the same color as the yarn previously used.

The lower front portion 5 of the leg 2 is preferably to be knitted simultaneously with the high splice 4 and in order to accomplish 50 this the remaining half of the series of needles upon which the tubular leg portion was previously formed will be actuated by a secondary set of knitting cams arranged to operate only upon said remaining needles 55 and as the yarn in the preferred construction of the stocking is at this point of the same color and weight as that forming the leg portion 2, a secondary yarn guide is preferably employed to present the yarn to the 60 needles acted upon by the said secondary knitting cams. By this means two sections of fabric will be constructed, one section, that is the section 5, will be composed of yarn substantially identical in character 65 with the yarn of the leg 2 while the yarn of

the other section 4 will be of the much heavier grade but preferably of the same color as the yarn of the leg, said sections of fabric consisting of parallel courses united at opposite sides of the leg of said stocking 70 in a seam 6 composed of the terminal loops of the fabric sections. These operations continue until the ankle 7 of the stocking, or a point adjacent thereto, is reached at which point the usual heel narrowing and widening operations are begun to produce the usual heel pocket, and during which operations the series of needles upon which the section 5 of the stocking has been formed and which are usually termed instep needles, are 80 withdrawn from action and the knitting continues on the needles upon which the high splice 4 was knitted.

Previous to the starting of the narrowing process of said heel at the ankle point 7 the 85 heavy silk yarn which forms said high splice is preferably withdrawn and in its place a heavy mercerized yarn of like weight and color as said silk yarn is used. This yarn follows a course from the point 7 or ankle 90 at one side of the foot along the broken line 8 to the point of the ankle at the opposite side of the foot, said course being substantially parallel with the course 3 at the top of the high splice.

95 From this line on the heavy mercerized yarn is employed until a point is reached in the narrowing operation of the heel preferably as indicated at 9 which constitutes the lower extremity of a so-called "drop heel" 100 and includes a plurality, preferably a majority of the heel narrowing courses and low enough to eliminate all possibility of the white foot of the stocking from showing above the top of the shoe, said line being 105 preferably co-incident with one of the minor narrowing courses of the heel, or in other words, said line terminates nearer the last narrowing course of the heel at 10 than it does to the ankle 7. When this line is 110 reached the heavy black mercerized yarn is withdrawn from the needles when the foot is to be white or formed from undyed yarn and the light colored or white mercerized 115 yarn of substantially the same weight and character is substituted therefor and knit into the heel for the completion of the narrowing thereof, and all of the widening courses of said heel back to the point of the ankle 7 and as far beyond said point 7 as 120 desired.

125 In some instances the reinforced mercerized yarn may be extended the entire length of the foot 11 and into the toe 12; or, I may extend it only a short distance beyond the ankle 7 as, for instance, to a line 13 indicating the extent of the heel area which is exposed to the greatest amount of wear. Upon the completion of the widening of said heel, that is, when the point 7 is reached, the 130

instep needles are again thrown into action and knitting continues thereon simultaneously with the knitting of the foot to form the seam 14 similar to the seam 6; said seam 5 14 extending from the ankle 7 to a point 15 at the toe where the usual narrowing operation begins. When the line 13 is reached in the knitting of the foot, an unreinforced mercerized yarn, i. e., one of lighter weight 10 or comprising fewer yarns, but similar in color to that forming the heel of the stocking may be substituted for said heavy mercerized yarn and knitting therewith continued to any desired point in the region of 15 the toe such, for instance, as the line 16 at which point the heavy mercerized yarn may again be supplied to the needles to effect the knitting of the toe 12 which is formed by the usual narrowing and widening operations. 20 The sections of fabric comprising the high splice 4, the lower front portion of the leg and the instep thereof, the section of the heel from the line 8 to the line 9, the remainder of the heel through the line 9 to the line 13, 25 the arch portion of the foot extending from the line 13 or the line 16 to the toe 12, are all preferably composed of partial courses formed of distinct yarns of any desired weight, color or quality; each being designed 30 so as to most economically withstand the particular degree of wear to which it is to be subjected and to eliminate all unnecessary expense in the production thereof. Furthermore, said stocking will be so formed that 35 the several areas will be capable of resisting to a substantially equal degree the wear to which they are exposed in order that the life of the several areas may be of substantially equal length, no one section thereof wearing 40 out before the other sections of the stocking. To reiterate, the section of the stocking including the high splice or reinforced ankle portion 4, and that portion 5 of the leg adjacent to but in front of said high splice and 45 which has been designated as the lower front leg portion, preferably compose what is called split fabric. That is, these areas are formed from distinct yarns in two sections which are united preferably at opposite sides 50 in seams 6, 6 composed of the terminal loops of said fabric sections 4 and 5. This method of knitting the high splice effects a considerable saving in yarn by omitting the floating yarns which are always present when the 55 high splice is formed by the interknitting of one or more extra yarns during the formation by rotary knitting of the front and back lower leg portions. Also there will be a saving in labor as there will be no floating yarns to be removed subsequent to the 60 knitting of the stocking.

Referring to Fig. 2, I have illustrated a stocking constructed substantially as hereinbefore described with the exception that 65 the high splice 4 is omitted. In this

form the leg portion 2' is of tubular formation down to the point 7' of the ankle at which point the narrowing of the heel takes place and when this point is reached a heavier yarn is supplied to the needles in 70 order to reinforce the entire heel portion of said stocking, said heavier yarn being incorporated therein along the line 8' and extending into a majority of the heel narrowing courses to the line 9' lying a sufficient 75 distance below the ankle 7', thus preventing the lighter colored yarn of the foot which adjoins said heavy yarn from being exposed to view.

The remaining portions of the heel, that 80 is, from the line 9' to the end 10' of the narrowing courses and through the widening courses beyond, the heel may be formed of a white or lighter colored yarn preferably of the same weight as that of the area between 85 the lines 8' and 9', thus insuring the desired amount of wear at the heel of the stocking without incurring any additional expense in the construction thereof which would be incurred if the silk yarn from which the 90 leg portion 2' is formed, were extended into the heel to the line 9'. The other sections of the stocking may be formed, if desired, in accordance with any of the methods hereinbefore described. 95

Having thus described one illustrative embodiment of my invention, I desire it to be understood that although specific terms are employed they are used in a generic and descriptive sense and not for purposes of limitation, the scope of the invention being set forth in the following claims: 100

1. A knitted stocking having the upper and lower portions of the foot composed of yarns of contrasting colors, the dividing line 105 of said yarns passing through the nominal ankle of a high splice extending substantially below the nominal ankle of the stocking, a portion of said high splice below said nominal ankle being composed of separate 110 yarn, like in color but unlike in character to the yarn of said high splice above said nominal ankle.

2. A knitted stocking having the upper and lower portions of the foot composed of 115 yarns of contrasting colors, the dividing line of said yarns passing through the nominal ankle of a high splice area terminating below the nominal ankle point on a line coincident with a minor heel narrowing course, 120 the portion of said high splice below said nominal ankle being composed of yarn like in color but unlike in character to the yarn of the leg portion and of said high splice above said nominal ankle. 125

3. A knitted stocking having the upper and lower portions of the foot composed of different yarns of contrasting colors, the dividing line of said yarns passing through the nominal ankle of a reinforced area extend- 130

5. ing from a line approximating the narrowing course of the heel pocket, the terminal loops of which interknit with the last widening course of said stocking, to a line coincident with a minor narrowing course of said heel pocket, the yarn composing said reenforced area being like in color but unlike in character to that composing the leg portions of said stocking.
- 10 4. A knitted sanitary stocking having the upper portion of the foot composed of dyed yarn and the lower portions thereof composed of undyed yarn, the dividing line of said yarns passing through the nominal ankle, a heel pocket composed of an equal number of narrowing and widening courses, a plurality of narrowing courses thereof being composed of a separate yarn similar in character but contrasting in color with 20 the yarn of the remaining portion of said heel.
- 15 5. That method of forming a knitted sanitary stocking which includes the formation in the vicinity of the heel from distinct yarn 25 of a high splice area which terminates adjacent to the nominal ankle of said stocking and in forming as a continuation of said high splice area a reenforced area composed of yarn unlike in character but alike in 30 color to that of the first mentioned reenforced area, said last mentioned area extending a substantial distance below said ankle, and then in forming the upper and lower foot portions from different yarns of 35 contrasting colors, the dividing line thereof passing through said nominal ankle.
- 40 6. That method of forming a knitted stocking which consists in effecting the knitting of the leg from dyed yarn to a point substantially above the nominal ankle of the stocking, then in knitting into the leg a reenforced area extending to the nominal ankle, then in effecting the knitting of a plurality of heel narrowing courses from a 45 different yarn of the same color as that of the leg, then in knitting the remaining narrowing courses of said heel and the widening courses thereof from an undyed yarn differing in character from that of the reenforced area above said ankle, and then in 50 knitting the lower and upper portions of the foot of different yarns, the dividing line of said yarns passing through the nominal ankle, the yarn of the upper foot portion being like in color to that of the leg and 55 the yarn of the lower foot portion being of undyed yarn.
7. The method of forming a knitted stocking which consists in effecting, by rotary knitting, the formation of the leg to a point 60 substantially above the nominal ankle of the stocking; then in effecting by reciprocatory knitting and from different yarns, the formation of two sections of fabric consisting respectively of the lower front leg portion 65 and a high splice united in a seam, the yarns composing said sections being of the same color, the latter section extending substantially to the nominal ankle, then in knitting a plurality of heel narrowing courses from 70 a different yarn or yarns like in color but unlike in character to the yarn of said high splice, then in knitting the remaining narrowing courses and the widening courses of the heel of a different yarn contrasting in 75 color with the yarn of said plurality of heel narrowing courses and then in knitting the lower and upper foot portions of different yarns, the dividing line of said yarns passing through the nominal ankle, the yarns composing said lower foot portion contrasting in color with the yarn composing said upper foot portion.
8. The method of forming knitted hosiery which consists in forming the leg and instep 85 portions from dyed silk yarn and in forming a high splice from a reenforced dyed silk yarn similar in color to that of said leg, said high splice area terminating adjacent to the nominal ankle, then in knitting a plurality 90 of the heel narrowing courses of a mercerized yarn substantially like in weight and color to the yarn of said high splice, and then in knitting the upper and lower foot portions of dyed silk yarn and undyed mercerized yarn respectively, the dividing line 95 of said yarns passing through the nominal ankle.
- In testimony whereof, I have signed my name to this specification.

ALDEI LANDRY.
